GAME DEVICE WITH ELECTRICAL SCORING MEANS

Armand E. Werle, Oakland, and Rudolph V. Miick, San Leandro, Calif.

Application April 20, 1948, Serial No. 22,206

17 Claims. (Cl. 273—88)

1

This invention relates to a game device to be played by two or more persons or by two or more groups of persons organized into teams, the game device being constructed to simulate an actual game, e. g., an athletic contest played by teams, such as baseball, football, or the like, wherein definite plays and/or playing situations occur. More particularly, the invention relates to a game device wherein each player or side is provided with one or more independently operable selectors having indicia representing different plays and/or playing situations encountered in actual games, and the game device is provided with an electrical scoring or result-indicating means which may be permanently energized or may be brought into operation intermittently through an indicator control switch after the players have made their selections on the selectors, the indicator control switch being operated either by one of the players, or by a neutral person acting as umpire or referee, or automatically, as by a relay, upon completion of the selections or after a predetermined time interval has elapsed.

The game device is constructed to indicate results which are dependent upon the settings of the selectors, and the results are such as would occur in an actual game, that is to say, they depend both upon chance and skill. Because the plays, decisions or playing situations indicated on the selectors correspond closely to those encountered in actual games, the game device is useful as an educational device for teaching strategy in the actual game represented; for this purpose the scoring or result indicating unit is preferably constructed so as to indicate thereon only results which are likely to follow from the selected situations and plays. The element of chance is introduced by providing a plurality of different results for a given combination of settings of two selectors, all of such alternate results being, preferably, likely to occur when plays selected by the selectors are made in an actual game.

Although the invention may be embodied in various forms to simulate or represent various athletic or sporting contests, it will be described herein as applied to a game of baseball, since this game affords an excellent diversity of plays and results, and, further, illustrates how the results may be controlled not only by the settings of the selectors but also by the score registered thereon. It should be understood that we do not thereby restrict the invention to the game of baseball.

It is an object of the invention to provide a game device which will simulate an actual game or contest, such as an athletic game played by teams, wherein each of two players or teams may make selections of plays and/or tactics and/or playing situations, and the results or score will be indicated, such results conforming to the

2

probable results in the actual game in which the selected plays, tactics or situations occur.

It is a further object to provide a game device of the type described wherein the indicated result or score may be registered and displayed, the registering unit being interconnected with the score or result-indicating unit to influence the indicated result or score.

Still another object is to provide a game device 10 of the type described having an electrical score or result-indicating unit provided with discriminator circuits for preventing indication of results which are impossible in the actual game because of the rules of the game and the playing 15 or score situation prevailing in such game, e. g., in a baseball game to prevent the indication of a "double play" when two outs have been registered, or to prevent a "caught off base" or "out stealing" result to be indicated when there are 20 no runners on base; or, in a football game, to prevent a field goal from being scored by a team not having the ball or having the ball in its own territory.

Another object is to provide an interesting 25 game device which will hold the interest of the players and wherein the players play against each other and not against the game.

Still another object is to provide a game which 30 may be embodied either as a unit for use in homes, clubs, or the like, or as a commercial, coin-controlled appliance.

A specific object is to provide a game device 35 representing a baseball game having a miniature representation of a playing field, wherein the status of the game, e. g., the number of men on bases, the pitch and hits, are indicated by lights located at the appropriate bases, in the pitcher's mound and in the batter's box, respectively. Ancillary thereto, it is an object to provide an 40 attractive game device affording spatial as well as mathematical similarity to the actual game by providing a miniature baseball diamond or field whereon results are indicated by lights located at points thereon where plays and results 45 of the type indicated may occur, e. g., by providing foul ball lights outside of the fair ball field, and by locating stolen base indicating lights near the bases, and infield single base hit lights within the infield.

Other objects of the invention will become apparent from a reading of the following detailed description, which is to be taken in connection with the attached drawings forming a part of this specification and illustrating one preferred specific embodiment of the invention, wherein:

Fig. 1 is a developed plan view of the game device, showing, in addition to the horizontal top, the four vertical sides as they would appear if bent upward;

Fig. 2 is a block diagram showing the power

supply circuit, control switches, and the main component parts of the game device;

Fig. 3 is a wiring diagram of the pitch selector and batter switches;

Fig. 4 is a wiring diagram of the hit selector and hit defense switches;

Fig. 5 is a wiring diagram of the base runners switch;

Fig. 6 is a wiring diagram of the outs switch;

Fig. 7 is a wiring diagram of the balls switch;

Fig. 8 is a wiring diagram of the strikes switch; and

Fig. 9 is a wiring diagram of the runs switch.

Briefly, according to the present invention we provide a pair of multi-position selector switches to be operated by opposed players, each switch being preferably only visible to the player or team operating the same and the switches having indicia indicating plays of the game represented by the game device. According to one common embodiment, wherein one defensive play is provided for each offensive play, one of the selector switches is a single circuit, multi-position switch of the non-shorting type (establishing only one connection for any position thereof) and the second selector has one circuit or movable contact arm corresponding to each position of the first switch, and has an equal number of positions. In such a combination the second switch has contacts equal in number to the square of the number of positions to which such second switch can be set, and one and only one contact is, at any one combination of settings, connected to and energized directly by the movable arm of the first switch, which may be connected through a control switch to a source of electrical power. By interconnecting selected contacts the number of different output circuits may be reduced to any desired number. The frequency or probability of any particular output circuit's being energized during a succession of random settings of the selectors is proportional to the number of contacts connected to such circuit. We may, however, modify the device by employing shorting type switches for establishing simultaneously connection to more than one output circuit to indicate results which may occur simultaneously. Moreover, we do not in every case have to provide the same number of positions for the two selector switches of the pair; in other words, we may represent a greater or a lesser number of offensive plays than defensive plays.

Some or all of the output circuits are connected to indicator lights, having appropriate indicia. These results are dependent upon the correlation between the settings of the two selector switches. Thus, when the first selector switch permits selection of a type of defensive play, e. g., a kind of pitch to be thrown by the pitcher, and the second selector switch permits selection of a kind of action expected by the player on the offensive, e. g., the kind of pitch expected by the batter, the circuits are arranged to yield results favorable to the player operating the first switch if the opponent expects and selects a play differing greatly in kind from that selected by the former, and vice versa.

A further feature of the invention is the provision of one or more secondary pairs of selector switches to be operated by the opposed players (or by other members of the opposed teams) interconnected similarly to the first pair of selector switches but bearing indicia relating to different types of plays or strategy in the game, e. g., the type of hit to be batted by the man at bat.

Although these switches may be arranged in various ways, we prefer to arrange a second pair of selector switches so that the player charged with predicting the play of his opponent when the first pair of switches is set, makes a decision which must be met or predicted by his opponent when the second pair of switches is set. For example, in baseball, the second pair of switches would enable the team at bat to select a type of hit, and the team in the field would select a type of hit to be expected and prepared for. In the specific case described the second pair of selector switches is energized only when the result of the combination of settings of the first pair of selectors is favorable to the player charged with predicting his opponent's play therein, e. g., when a hit is obtained by the batter; in other games, however, the secondary switches may come into play also when the results of the first pair of switches is not favorable to such player, e. g., in football a penalty may be applied against either side regardless of which one has the ball and regardless of whether a gain is made.

The game device is further provided with other switches for varying the results as a function of the score or situation, e. g., in baseball, depending upon the number of men on base, the number of strikes and outs, and in football, depending upon the downs and the proximity to the goal line, etc. Also, there may be a switch for indicating the score. These added features are, however, optional insofar as the general concept of the invention is concerned.

The game device will be better understood by referring to the drawings. In Fig. 1 we have shown a box having an upper, outer face providing a table 10, and vertical side walls 11a, 11b, 11c and 11d. The table has indicia thereon representing a baseball diamond and lights 12, 13 and 14 representing first, second and third bases. All other lights have indicia associated therewith as follows: "Hit" light 15 in the batter's box; "Caught off base" light 16; "Double play" light 17; "Out stealing" light 18; "Triple play" light 19; three "Strikes" lights 20, 21 and 22; three "Outs" lights 23, 24 and 25; two "Foul ball" lights 26 and 27; "Hit by pitch" light 28; "Wild pitch" light 29; "Overthrown" light 30; "Error-1 base" light 31; "Fielder's choice" light 32; "Stolen base" light 33; "Double steal" light 34; "Out-runner's advance" light 35; infield "Single" light 36; two outfield "Single" lights 37 and 38; "Double" light 39; "Triple" light 40; "Home run" light 41; four "Balls" lights 42, 43, 44 and 45; eight "Runs" lights 46 to 53, inclusive; and a "Pitch" light 54 in the pitcher's box. These lights may be of contrasting colors to indicate kinds of results; thus, we may use red for lights 12 to 25; yellow for lights 26 to 31; white for lights 32 to 35; green for lights 36 to 53, all inclusive; and orange or red for light 54. Any small, low voltage bulb, such as peanut or flashlight lamps, may be used. We prefer to install lights brighter than the others for lights 22, 25, 41 and 45, to indicate a strike-out, retirement of the side, a home run and a walk, respectively.

The lights are energized by electric power supplied through an electric cord attached to a receptacle 55 in the rear wall 11d, through circuits to be described. A main switch 56 may be provided to control all circuits, but may be omitted because power can be cut off by disconnecting the cord. When switch 56 is closed the runs lights 46 to 53, inclusive, can be selectively illuminated.

one at a time, by a multi-position single circuit runs switch 57 on the right side 11c (Figs. 1, 2 and 9), independently of all other switch settings. Further, base runners lights 12, 13 and 14 can be illuminated in any combination by a base runners switch 58 in front wall 11b (Figs. 1, 2 and 5); balls lights 42 to 45, inclusive, may be illuminated cumulatively through a balls switch 59 in front wall 11b (Figs. 1, 2 and 7); strikes lights 20, 21 and 22 may be cumulatively illuminated through a strikes switch 60 in left side wall 11a (Figs. 1, 2 and 8); and outs lights 23, 24 and 25 may be cumulatively illuminated through an outs switch 61 in left side wall 11a (Figs. 1, 2 and 6). Although switches 59 to 61, inclusive, are, like switches 57 and 58, directly connected to the transformer for power, they do not illuminate the lights 22, 25 and 45 directly but merely connect these lights to other circuit elements energized by the selector switches, to be described. Switches 58 to 61 also control discriminator circuits, as will become evident hereafter.

The left side 11a is further provided with a normally open, spring return index "Pitch" switch 62 (Figs. 1 and 2); a "Pitch selector" switch 63 (Figs. 1, 2 and 3); and a "Hit defense" switch 64 (Figs. 1, 2 and 4). The front wall 11b further carries a "Batter" switch 66 (Figs. 1, 2 and 3) and a "Hit selector" switch 65 (Figs. 1, 2 and 4). The switches 63 and 66 constitute a pair of correlated selector switches, and switches 64 and 65 another pair of correlated selector switches. The game device is arranged so that the player or players "in the field" is/are on the left side for operating switches 60 to 64, inclusive, while the player or players "at bat" is/are at the front for operating switches 57, 58, 59, 65 and 66. Neither player can see the opponent's switches.

Referring to Fig. 2, the circuit comprises a transformer 67, e. g., one receiving 110 v., A. C. from receptacle 55 and delivering 2.5 v. in the secondary, one side of which is grounded at 68. One side of all lights is similarly grounded, so that only one power circuit need be described. All points marked 69 are interconnected and energized when the switch 56 is closed. The live side of the secondary transformer coil is further connected to one side of the pitch switch 62, the controlled side of which is connected to the movable arm of the pitch selector switch 63 by wire 70 and also to the "Pitch" light 54 at the pitcher's mound by a wire PM. The "scoreboard" shown in Fig. 2 represents, in its entirety, the table 10 and the indicia and lights thereon. It will be seen that the light 54 is illuminated each time the switch 62 is closed, to indicate a pitch or throw to a baseman.

Switch 63, shown in Figs. 3, is a single-circuit, eleven-position switch. Eleven wires P1 to P11, inclusive, leading from different contacts, are connected to the eleven separate contact arms of eleven-circuit, eleven-position switch 66, such as a gang switch indicated in the drawing. While the latter has 121 contact points, these are interconnected to provide only twelve separate output circuits Q1 to Q12, inclusive. Circuit Q1, which is energized when a hit is registered, is branched and connected both to the "Hit" light 15 and to the movable arm of the hit selector switch 65. Circuits Q2 and Q3 are connected to the balls switch 59 and strikes switch 60, respectively; five wires, Q4 to Q8, inclusive, are connected to lights on the scoreboard as indicated in Table I, below; and four wires, Q9 to Q12, inclusive, are connected

to the base runners switch 58. The designations of the wires are as follows:

TABLE I

5	Output Circuit	Relative Frequency	Designation	Connection
Q1		27	Hit	Hit light 15 and switch 65.
Q2		39	Ball	Switch 59.
Q3		28	Strike	Switch 60.
Q4		5	Foul ball #1	Light 26.
Q5		9	Foul ball #2	Light 27.
Q6		1	Hit by pitch	Light 28.
Q7		1	Wild pitch	Light 29.
Q8		1	Error—1 base	Light 31.
Q9		2	Stolen base #1	Switch 58.
Q10		2	Stolen base #2	Do.
Q11		2	Caught off base	Do.
Q12		6	Out—stealing	Do.

The relative frequency, given in the second column of Table I, indicates the relative frequency 20 at which any stated output circuit would be energized, assuming a succession of random settings of the switches 63 and 66. These numbers correspond to the number of output contacts of switch 66 connected to the respective circuit. The 25 probability of energizing any circuit may be obtained by dividing its relative frequency by 121, the total number of contacts.

Switch 65, shown in Fig. 4, is a single-circuit, nine-position switch. Nine wires K1 to K9, inclusive, leading from different contacts, are connected to the nine separate contact arms of nine-circuit, nine-position switch 64, such as a gang switch, having 81 contacts, some of which are interconnected to provide eleven output circuits K1 to K11, inclusive, as shown in Table II:

TABLE II

40	Output Circuit	Relative Frequency	Designation	Connection
K1		9	Infield single base hit	Light 36.
K2		10	Double base hit	Light 39.
K3		3	Triple base hit	Light 49.
K4		2	Home run	Light 41.
K5		1	Single base hit and overthrow	Lights 30 and 38.
45	K6	11	Outfield single base hit	Light 37.
K7		9	Out—runners advance	Switch 58.
K8		7	Double play	Do.
K9		2	Triple play	Do.
K10		9	Fielders choice	Do.
50	K11	18	Fly—out or Hit—out	Switch 61.

As is evident, the eleven output circuits correspond to eleven different results of hitting a ball. Circuits K1 to K6 are connected directly to the result lights on the table 10. Circuits K7 to K11, however, do not energize lights on the score-board directly, but energize discriminator circuits. Thus, the results corresponding to K7 to K10 are dependent upon the number of runners on bases and are, therefore, further controlled by switch 60. 58. Similarly, since it is desired to illuminate light 23, 24 or 25 if there are no, one or two previous outs in the inning, respectively, circuit K11 is fed to switch 61.

Switch 58, shown in Fig. 5, is an eleven-circuit, eight-position switch: The first three circuits are energized continuously from source 69 and energize output circuits BR1, BR2 and BR3; the next four circuits, comprising separate moving contact arms, are energized by circuits K7 to K10, inclusive, and selectively energize one of thirty-two contacts, which are interconnected to provide five output circuits BR8 to BR12, inclusive; the last four circuits, also comprising separate contact arms, are energized by circuits Q9 to Q12, inclusive, and selectively energize thirty-two con-

tacts, which are interconnected to provide six output circuits, BR4 to BR7, inclusive, BR13 and BR14. These output circuits are as follows:

TABLE III

Output Circuit	No. of Contacts	Designation	Connection
BR1	4	First base	Light 12.
BR2	4	Second base	Light 13.
BR3	4	Third base	Light 14.
BR4	10	Caught off base	Light 16.
BR5	10	Out—stealing	Light 18.
BR6	7	Stolen base	Light 33.
BR7	1	Double steal	Light 34.
BR8	5	Fielders choice	Switch 61.
BR9	6	Out—runners advance.	Do.
BR10	15	Double play	Do.
BR11	2	Triple play	Do.
BR12	4	Out	Switch 61, via circuit K11.
BR13	1	Ball	Switch 59, via circuit Q2.
BR14	3	Strike	Switch 60, via circuit Q3.

Circuit BR12 energizes the "out" circuit in the same manner as an out over circuit K11. The results according to circuits BR8 to BR10, inclusive, are modified in the outs switch 61 through discriminator circuits so as to indicate a simple out when there are already two outs in the inning; and to change a triple play into a double play when there is already one out, etc.

The switch 61, shown in Fig. 6, is a seven-circuit, three-position switch, of which the first movable contact arm is connected to circuits K11 and BR12, as also to "output" circuit T8 by an internal connection; the second and third movable contact arms are constantly supplied with power from source 69. These first three arms make contact selectively with nine contacts, which are interconnected to provide three output circuits T1, T2 and T3. The remaining four movable arms are connected to circuits BR8 to BR11, respectively, and selectively energize twelve contacts, some of which are interconnected to provide four external output circuits T4 to T7, inclusive, and one internal output circuit T8. These output circuits are as follows:

TABLE IV

Output Circuit	Designation	Connection
T1	First out	Light 23.
T2	Second out	Light 24.
T3	Third out	Light 25.
T4	Fielders choice	Light 32.
T5	Out—runners advance	Light 35.
T6	Double play	Light 17.
T7	Triple play	Light 19.
T8	One out	Internal connection to first movable contact arm of same switch, via K11.

The balls switch 59, shown in Fig. 7, is a four-circuit, four-position switch, the first movable contact arm of which is connected to circuits Q2 and BR13, and the other three arms of which are constantly energized from source 69. These arms make contact with sixteen different contacts, some of which are interconnected to provide four output circuits as follows:

10

TABLE V

Output Circuit	Designation	Connection
B1	First ball	Light 42.
B2	Second ball	Light 43.
B3	Third ball	Light 44.
B4	Fourth ball	Light 45.

The strikes switch 60, shown in Fig. 8, is a three-circuit, three-position switch, the first movable contact arm of which is connected to circuits Q3 and BR14, and the remaining two arms of which are constantly energized from source 69. These arms make contact with nine contacts, some of which are interconnected to provide three output circuits as follows:

30

TABLE VI

Output Circuit	Designation	Connection
S1	First strike	Light 20.
S2	Second strike	Light 21.
S3	Third strike	Light 22.

The runs switch 57, shown in Fig. 9, is a simple single-circuit, nine-position switch the movable arm of which is constantly energized from source 69. It has an open position and eight contacts connected, respectively, to circuits R1 to R8, inclusive, which are connected to lights 46 to 53, respectively, for illuminating one light at a time.

The connections to the various contacts of the first three of these, viz., the switches shown in Figs. 3, 4 and 5, are difficult to follow, and to present more readily understandable indication of the circuits established by various settings, the following three tables are presented. In these tables, the circuit indicated at the intersection of any horizontal row and vertical column represents the output circuit established when the circuits described at the left are energized and the switch is set to the position shown at the top:

TABLE VII

11. Q12 Out Stealing.....	BR13	BR5	BR5	BR5	BR5	BR5	BR5	BR5

Note.—NC indicates no contact connection.

For example, when the first player, representing the side in the field, moves his pitch selector switch 63 to its seventh position (indicating that he intends to pitch a "curve"), and the second player, representing the side at bat, moves his 45 batter switch 66 to its ninth position (indicating that he expects a "slow ball" to be pitched), the subsequent closing of the pitch switch 62 causes the output circuit Q3 to be energized. This result is indicated in Table VII and may be traced on the wiring diagram of Fig. 3, wherein the circuit is: wire 70—movable arm of switch 63—seventh stationary contact of switch 63—circuit wire P7—seventh movable arm of switch 66—ninth stationary contact of the seventh section of switch 66—circuit Q3. As is shown in Figs. 2 and 8, circuit Q3 is connected to the strikes switch 69, and causes the lowest numbered, un-illuminated strikes light 20, 21 or 22 to be illuminated. The indicated result of the play is, therefore, a strike; this result for circuit Q3 is, further, given in Table I. It should be noted that with this result the switches 64 and 65 are not energized, and it is immaterial how they were positioned.

If, in the example of the preceding paragraph, the second player had moved his batters switch 66 to its sixth position (indicating that he expected a "roundhouse" to be pitched), the result would have been a hit instead of a strike. Thus, in this event, the closing of the pitch switch 62 causes the output circuit Q1 instead of output circuit Q3 to be energized. This result is similarly tabulated in Table VII, and can likewise be traced in Fig. 3 as follows: wire 70—

movable arm of switch 63—seventh stationary contact of switch 63—circuit wire P7—seventh movable arm of switch 66—sixth stationary contact of the seventh section of switch 66—circuit Q1. As is indicated in Table I, circuit Q1 represents a hit, and, as shown in Fig. 2, a branch of circuit Q1 leads to the scoreboard, where it energizes the hit light 15. Another branch of circuit Q1 energizes the hit selector switch 65, as is shown in Figs. 2 and 4.

When a hit is obtained, eleven different results are possible, as tabulated in Table II. Which of these results will occur depends upon the positions of the hit selector switch 65 and the hit defense switch 64. For example, if in the situation of the example of the immediately preceding paragraph the second player had moved his hit selector switch 65 to its fourth position (indicating that he intended to hit a "line drive") and the first player had moved his hit defense switch 64 to its second position (indicating that he expected the batter to hit a "sacrifice"), the subsequent closing of the switch 62 and energization of circuit Q1 would have resulted in the energization of output circuit K2 which, according to Table II, is a double base hit, and is connected to the double base hit light 39 on the scoreboard. The connection of circuit K2 to the scoreboard is shown in Fig. 2. The 70 above-stated result of these two positions of the switches 64 and 65 is indicated in Table VIII, and may, moreover, be traced on the wiring diagram of Fig. 4, wherein the circuit is: circuit wire Q1—movable arm of switch 65—fourth stationary contact of switch 65—circuit wire H4—fourth

11

movable arm of switch 64—second stationary contact of the fourth section of switch 64—output circuit K2.

When the switches 64 and 65 are positioned to result in the energization of one of the circuits K7 to K10 when a hit is obtained, the resulting signal passes through the base runner's switch 58, by one of the four wires shown on Fig. 2. For example, if the switches 63, 64 and 65 are positioned as described in the two preceding paragraphs, but the first player positions his hit defense switch 64 to its fourth position (indicating that he expects a "line drive" to be hit) the K9 circuit is energized instead of the K2 circuit. This result is tabulated in Table VIII and may be traced in Fig. 4 as follows: circuit wire Q1—movable arm of switch 65—fourth stationary contact of switch 65—circuit wire H4—fourth movable arm of switch 64—fourth stationary contact of the fourth section of switch 64—output circuit K9. As shown in Table II, the K9 circuit corresponds to a triple play. Circuit K9 is not, however, connected directly to the triple play light 19, because a triple play is possible only when there are at least two men on bases and, in addition, there are no outs in the inning. To take care of situations wherein these conditions are not satisfied we provide discriminator circuits, which are described more completely hereinafter.

As will be apparent from the wiring diagrams, the H and K circuits, and those energized thereby (including circuits BR8 to BR12, inclusive) are energized only when circuit Q1, representing a hit, is energized; this occurs on an average of 22.3% of the times that the switches 63 and 66 are set, assuming random settings. In these instances circuits Q2 to Q12 are not energized. It follows that the pair of selector switches 65 and 64 establish energized circuits only when a hit is indicated by the first pair of selector switches 63 and 66.

According to one simplified embodiment, we may omit switches 64 and 65 and the circuits controlled thereby, and use only a single pair of selector switches. In this simplified form, the Q1 circuit may be sub-divided into several separate sub-circuits connected to different groups of contacts on switch 66 to indicate various types of hits on different lights, as will be evident to persons familiar with such devices. However, by providing two pairs of selector switches the game is made far more interesting and comes closer to simulating an actual game. Moreover, this permits four players to participate and introduces the element of trying to outguess the opponent into both sides; thus, not only must the batter select a pitch similar to that to be thrown by the pitcher, but the pitcher (or his partner) must select a type of hit corresponding to that to be batted by the batter.

While we have, in this description and drawings, made reference to well-understood multi-position switches with movable contact arms, we desire it understood that the switches may take other forms more readily adapted for mass production, e. g., cam actuated reciprocating switches, etc.

PLAYING THE GAME

Playing the game proceeds by following the steps followed in an actual major league baseball game. When played by two players they take positions at different sides, the player representing the side in the field (herein for convenience

12

referred to as the "first player") facing the left side 11a, and the player representing the side at bat (herein called the "second player") facing the front 11b.

5 The switch 56 being closed, switches 57 to 61 being set to their first positions (to darken all lights) and switch 62 being open, the first player selects a pitch and a hit defense on switches 63 and 64, while the second player selects an expected pitch and a hit on switches 66 and 65, respectively. The first player then depresses switch lever 62, thereby energizing circuits 70 and PM to illuminate light 54 in the pitcher's mound, and, in addition, a score or result light, 15 depending upon the output circuit energized by the selector switches and, in the case of output circuits Q2, Q3, Q9 to Q12, inclusive, and K7 to K11, inclusive, depending also upon the playing situation registered by the switches 58, 59, 60 or 61.

20 The switch 62 is then released to permit it to open, and the previously indicated result is registered by manual operation of one of the registering devices, i. e., by turning the pointer of one or more of the switches 51—61. Thus, if the result was a strike or an out (which would be indicated by the illumination of light 20 or 23, respectively) the first player operates switch 60 or 61, respectively, to its second position. If 25 the result was a ball or a base hit (which would be indicated by the illumination of light 42, or one of the other lights, such as 36—41, respectively), the second player operates switch 59 to its second position, or switch 58 to the proper position. Runs are registered by operating switch 57.

30 After the result has been registered the players make new selections and the play continues until the second player has three outs, according to the well understood rules of baseball.

35 As indicated on the drawing, the selections which can be made on switches 63 and 66 are those listed in Table VII, while those which can be made on switches 64 and 65 are those listed 40 in Table VIII. These selections have names well understood in baseball, but may, of course, be varied to provide different types of plays to conform to local terminology. It is believed to be necessary herein to explain the meanings of only 45 a few of the less universally known expressions:

50 A roundhouse is an exaggerated curve, normally away from the batter, a ball that does not have the sharp "break" of a true "curve ball."

55 A crossfire is similar to a roundhouse but curves toward the batter.

A slider is thrown so that it "breaks" or curves toward the batter as it crosses the plate.

A sinker is thrown so that it "breaks" or drops toward the ground as it crosses the plate.

60 A screwball is thrown so that it appears to "corkscrew" as it approaches the batter.

65 A ball is thrown intentionally slightly wide of the plate to induce the batter to swing and miss; if not swung at it is a ball. In contrast, a pitch out is thrown intentionally wide of the plate to "walk" a batter or to enable the catcher to catch the ball quickly and catch a runner off base.

A Texas leaguer is a fly ball that is hit just too far for an infielder to catch but not far enough to reach the outfields.

A hit and run is made when the runner is about to start running as the pitcher starts his pitch, and the batter must hit to protect the runner. It is often used when the runner is at 75 first and, if properly executed, gets the runner

to third base; it also often results in a double play.

DISCRIMINATOR CIRCUITS

It should be noted that the electrical scoring and result-indicating circuits passing through switches 58, 59, 60 or 61 are provided with discriminator features. For example, when a ball has been registered on balls switch 59, the first ball light 42 remains continuously illuminated and when the selector switches are set to indicate the next ball this result will be indicated by the illumination of the next lowest numbered un-illuminated ball light 43 when the switch 62 is closed. Similarly, the strikes and outs are indicated by illuminating the light next to the previously illuminated light.

The discriminator action of the base runner's switch 58 and the outs switch 61 in changing some of the results in circuits Q9 to Q12 and K7 to K10 was previously referred to. For example, the "fielder's choice" circuit K10 is not connected directly to fielder's choice light 32 and circuit T10, but to the movable contact arm of the seventh section of the base runner's switch 58 (Fig. 5) where circuit K10 is connected to one of three different output circuits:

(a) When there are runners on any one base or on first and third bases, or on second and third bases, all movable contact arms of switch 58 are either in their second, third, fourth, sixth or seventh positions (as is evident from the indicia on Fig. 1 opposite the pointer of switch 58). It is evident from Fig. 5 that, in this position, the circuit K10 is connected through the seventh movable contact arm to the output circuit BR8, and the signal will remain a "fielder's choice." This output circuit goes to the out switch 61, as shown in Figs. 2 and 6, where it energizes the movable contact arm of the fourth section. If no out or if only one out has been registered on switch 61, all of its movable contact arms are in their first or second positions; in either of these positions the circuit BR8 will be connected to the output circuit T4 and fielder's choice light 32. Only in with these combinations of settings of switches 58 and 61 does the signal in circuit K10 remain a "fielder's choice." If two outs were previously registered on the out switch a "fielder's choice" is an inappropriate indication and the discrimination action of switch 61 prevents such an indication. Thus, when two outs are registered on this switch, all of its movable contact arms are on their third contacts, and the circuit BR8 will be connected through the fourth movable contact arm and internal circuit T8 to the first movable contact arm of the same switch and, through the latter, to output circuit T3 and the third out light 25, whereby the "fielder's choice" is changed into an "out."

(b) When there are no runners on bases a "fielder's choice" is obviously impossible, and to avoid an indication the signal is changed to an "out" by the base runner's switch 58. Thus, with no runners on bases, the movable contact arms of switch 58 are on their first contact points (in the positions illustrated in the drawing) whereby the circuit K10 is connected to the output circuits BR12 and K11, changing the signal to an "out." Circuits BR12 and K11 are connected to the first movable contact arm of out switch 61, through which one of the three outs circuits T1, T2 or T3 is energized, depending upon the number of outs registered for the current inning. This will cause the next lowest out light 23, 24 or 25 on the score-

board to be illuminated, these connections being tabulated in Table IV.

(c) When there are runners on first and second bases, or if there are runners on all bases, the movable contact arms of switch 58 are in their fifth or eighth positions, respectively; hence, as is evident from Fig. 5, in either of these situations the seventh section of this switch will connect the circuit K10 to the output circuit BR10, thereby changing the "fielder's choice" into a "double play." This output circuit goes to the sixth movable contact arm of the out switch 61. If no out, or if only one out has been registered on switch 61, circuit BR10 is connected to output circuit T6, energizing double play light 17. However, when two outs were previously registered, a double play is obviously impossible; in this situation the switch is in its third position and the circuit BR10 is connected through the fourth movable contact arm and the internal circuit T8 to the first movable contact arm of the same switch and, through the latter, to output circuit T3 and the third out light 25, whereby the signal is changed into an "out."

25 The "out-runner's advance" circuit K7 similarly goes to the fourth movable contact arm of the base runner's switch where it will change to an "out" through circuits BR12 and K11 unless there is at least one runner on the bases. If there are runners on first and second bases, it will change to the "double play" circuit BR10 which is further controlled in the out switch as described in the foregoing paragraph; in all other situations it will remain "out-runner's advance" and energize circuit BR9, which goes to the out switch. There it will be changed to an "out" through internal circuit T8 if there are already two outs, but will remain an "out-runner's advance" when there are less than two outs and energize circuit T5 and out-runner's advance light 35.

The "double play" circuit K9 also goes to the base runner's switch where it is connected to the movable contact arm of the fifth switch section and will change to an "out" through circuits BR12 and K11 unless there is at least one runner on the bases. If there are any runners on the bases, it will remain a "double play," energizing circuit BR10, going to the out switch 61 where the signal is further conditioned by the number of outs registered as described above.

The "triple play" circuit K9 is connected to the sixth movable arm of the base runner's switch 58 and is thereby changed to an "out" through circuits BR12 and K11 unless there are at least two runners on the bases. If there is only one runner on the bases, or if there are runners on second and third bases, or on first and third bases, it will change to a "double play," energizing circuit BR10, which is further controlled in the out switch as described above. If there are runners on first and second bases, or if the bases are full, it will remain a "triple play," energizing circuit BR11 to the out switch 61. At the out switch the "triple play" is changed to an "out" through internal circuit T8 if there are already two outs registered; if there is one out, it will change to a "double play," energizing circuit T6 and double play light 17; and if there are no previous outs it will remain a "triple play," energizing circuit T7 and triple play light 19.

The "caught off base" circuit Q11 is changed to a "strike" by the tenth movable contact arm of the base runner's switch, energizing circuit BR14 to strikes switch 60, unless there is at least

one runner on the bases. When there is at least one runner on the bases it will remain "caught off base" and energize circuit BR4 and caught off base light 16.

The "out stealing" circuit Q12 first goes to the eleventh movable contact arm of the base runner's switch, where it will change to a "ball," energizing circuit BR13 to ball's switch 59, unless there is at least one runner on the bases. With any runners on the bases it will remain "out stealing" and energize circuit BR5 and out stealing light 18.

The "stolen base #1" circuit Q9 is changed by the eighth movable contact arm in the base runner's switch to a "strike," energizing circuit BR14 to strikes switch 60, unless there is at least one runner on the bases. If there are runners on second base, or on first and third bases, or on second and third bases, it will change to "out stealing," energizing circuit BR5 and out stealing light 18. If there are runners on first base, or on third base, or on first and second bases, or on all bases, it will become a "stolen base" and energize circuit BR6 and stolen base light 33.

The "stolen base #2" circuit Q10 is changed by the ninth movable contact arm in the base runner's switch to a "strike," energizing circuit BR14 to strikes switch 60, unless there is at least one runner on the bases. If there are runners on third base, or on second and third bases, or on all bases, it will change to "caught off base" and energize circuit BR4 and caught off base light 16. If there are runners on first and second bases, it will change to a "double steal" and energize circuit BR7 and double steal light 34. If there are runners on first base or second base, or on first and third bases, it will become a "stolen base" and energize circuit BR6 and stolen base light 33.

Certain "ground rules" must be agreed upon before playing the game. Such rules may, for example, provide that when a fielder's choice is indicated the most advanced base runner is always put out. Similar rules may be made to cover situations arising from double play, caught off base, out stealing, stolen base, double steal, single and overthrow, hit by pitch, wild pitch, infield singles, and outfield single indications. Since such rules may be formulated as desired, they need not be presented herein. We may, however, provide additional discriminator circuits, of the type described above, to cover any or all of the situations covered by the ground rules; conversely, we may eliminate some of the discriminator circuits and arrange for conflicting or doubtful situations by ground rules, it being possible to construct our game device to any degree of complexity desired.

We claim as our invention:

1. A game device representing a game played by two or more sides comprising a source of electric power, a plurality of independently operable selector switches having a multiplicity of selectable points of contact and connected to said source of power, an electrical network connected to said switches and providing a plurality of output circuits, each switch being located to be operated by one of several opposed players out of view of opposing players to energize said output circuits selectively, indicia for said selector switches indicating plays in said game, a plurality of lights connected to said output circuits for indicating different results in said game consequent upon the plays indicated on said indicia at least one of said lights indicating a potentially impossible result which, under the rules of the game, 75

is impossible in certain playing situations, a multi-position registering device having a multi-position switch positioned thereby and indicia for indicating a plurality of playing situations in said game including said playing situations, and a discriminator circuit connected to and selectively conditioned by said last-named switch and interposed between said light indicating a potentially impossible result and its output circuit for disconnecting said output circuit from said light and connecting it instead to another light indicating a result which is possible with the playing situation registered by said registering device.

15 2. In combination with the device according to claim 1, a normally open switch for normally disconnecting said source of power.

20 3. A game device representing a baseball game comprising a source of electric power, a pitch selector switch, a batter selector switch, said switches having a multiplicity of selectable points of contact and being connected to said source of power, an electrical network connected to said switches and providing a plurality of output circuits, said switches being adapted to be operated independently by opposed players, each switch being visible only to the player operating the same to energize said output circuits selectively, indicia for said selector switches indicating different

25 kinds of pitches, a plurality of result-indicating lights connected to said output circuits for indicating results consequent upon a kind of pitch selected on the pitch selector switch being thrown to a batter expecting a pitch of the kind selected on the batter selector switch, indicia for said lights indicating the said results at least one of said lights indicating a potentially impossible result which, under baseball rules, is impossible in certain playing situations, a multi-position registering device having a multi-position switch positioned thereby and indicia for indicating a plurality of playing situations in said game including said playing situations, and a discriminator circuit connected to and selectively conditioned by said last-named switch and interposed

30 between said light indicating a potentially impossible result and its output circuit for disconnecting said output circuit from said light and connecting it instead to another light indicating a result which is possible with the playing situation registered by said registering device.

35 4. In combination with the game device according to claim 3, a table having indicia representing in miniature, a baseball playing field, at least some of said result-indicating lights being mounted on said table.

40 5. A game device representing a baseball game comprising a source of electric power, a hit selector switch, a hit defense selector switch, said switches having a multiplicity of selectable contact points and being connected to said source of power, an electrical network connected to said switches and providing a plurality of output circuits, said switches being adapted to be operated independently by opposed players to energize said circuits selectively, indicia for said selector switches indicating different kinds of hits, a plurality of result-indicating lights connected to said output circuits for indicating results consequent

45 upon a hit of the kind selected on the hit selector switch being batted when the players in the field expect a hit of the kind selected on the hit defense selector switch, indicia for said lights indicating the said results, at least one of said lights indicating a potentially impossible result

which is, under baseball rules, impossible when a minimum number of runners is on bases, a multi-position base runner-registering device having a multi-position switch and indicia for indicating the runners on bases, and a discriminator circuit controlled by said last-named switch and interposed between said result-indicating light and its output circuit for disconnecting said output circuit from said light and connecting it instead to another light indicating a result which is possible with the number of runners on base registered by said base runner-registering device.

6. A game device representing a baseball game comprising a source of electric power, a hit selector switch, a hit defense selector switch, said switches having a multiplicity of selectable contact points and being connected to said source of power, an electrical network connected to said switches and providing a plurality of output circuits, said switches being adapted to be operated independently by opposed players to energize said circuits selectively, indicia for said selector switches indicating different kinds of hits, a plurality of result-indicating lights connected to said output circuits for indicating results consequent upon a hit of the kind selected on the hit selector switch being batted when the players in the field expect a hit of the kind selected on the hit defense selector switch, indicia for said lights indicating the said results, at least one of said lights indicating a potentially impossible result which is, under baseball rules, possible only when not more than a maximum number of outs have occurred in an inning, a multi-position out-registering device having a multi-position switch and indicia for indicating the number of outs, and a discriminator circuit controlled by said last-named switch and interposed between said result-indicating light and its output circuit for disconnecting said output circuit from said light and connecting it instead to another light indicating a result which is possible with the number of outs registered by said outs-registering device.

7. A game device representing a game played by two or more sides comprising a source of electrical power, two pairs of independently operable, multi-position selector switches, one switch of each pair being disposed to be operated by one of two opposed players and the other switch of each pair being disposed to be operated by the other player, each switch being visible only to the player operating the same, indicia for the first pair of switches indicating a first set of plays in said game, indicia for the second pair of switches indicating a second set of plays in said game, a plurality of electrical first output circuits selectively energized jointly by the first pair of switches representing results consequent upon plays selected by the opposed players and set on said first pair of switches, at least one of said first output circuits being connected to said second pair of switches, a plurality of electrical second output circuits selectively energized jointly by the second pair of selector switches upon energization of said one first output circuit by the first pair of switches representing results consequent upon plays selected by the opposed players and set on said second pair of switches in conjunction with the result corresponding to the said one first output circuit, result-indicating lights for said first output circuits and result-indicating lights for said second output circuits for indicating results represented by said output circuits.

8. A game device representing a two-sided game comprising two pairs of independently operable,

selector switches having a multiplicity of selectable points of contact, one switch of each pair being adapted to be operated by one of two opposed players and the other switch of each pair being disposed to be operated by the other player, indicia for the switches of the first pair indicating a first set of plays in said game, indicia for the switches of the second pair indicating a second set of plays in said game, each pair of switches being interconnected to establish an electrical connection from an input circuit selectively to several output circuits representing results consequent upon plays selected by the opposed players and set on the respective pairs of switches, a source of electrical energy for the input circuit of said first pair of switches, the input circuit of said second pair of switches being connected to at least one output circuit from said first pair of switches, a plurality of result-indicating lights connected to at least some of the output circuits of each of said pairs of switches, and indicia for said lights indicating results consequent upon the selected plays by opposed players.

9. In combination with the game device according to claim 8, a fifth selector switch having a multiplicity of points of contact operable to register a situation in the game, and a discriminator circuit connected to and selectively conditioned by said fifth switch and interconnected between at least some of said output circuits and said result-indicating lights for disconnecting said lights from their respective output circuits and connecting other lights to said output circuits in accordance with the situation in the game.

10. In combination with the game device according to claim 9, a sixth selector switch having a multiplicity of points of contact operable to register a different type of situation in the game, and a second discriminator circuit connected to and selectively conditioned by said sixth switch and interconnected between the discriminator circuit of said fifth switch and at least some of the result-indicating lights for disconnecting said discriminator circuits of the fifth switch from said last-named lights and connecting them instead to other lights in accordance with the said different type of situation in the game.

11. A game device representing a two-sided game comprising a pair of independently operable, multi-position selector switches adapted to be operated by opposed players, indicia for said selectors indicating plays in the game, a plurality of output circuits jointly controlled by said selector switches, a plurality of result-indicating lights, for indicating results consequent upon the selected plays by opposed players in said game, a separate multi-position switch operable to register a situation in the game, and a discriminator circuit connected to and selectively conditioned by said separate switch and interconnected between at least some of said output circuits and said lights for connecting different ones of said lights to said output circuits for indicating results in accordance with the situation of the game.

12. A game device representing a baseball game comprising (1) a multi-position pitch selector switch, (2) a multi-position batter switch, (3) a multi-position hit selector switch and (4) a multi-position hit defense switch, said switches being independently operable disposed relatively so that the first and fourth named switches are operable by a first player and the second and third named switches are operable by a second player, indicia for the first and second switches representing

types of pitches, indicia for the third and fourth switches representing types of hits, a source of electrical energy, said first and second switches being interconnected to establish an electrical connection from said source of electrical energy selectively to several first output circuits, said third and fourth switches being interconnected to establish an electrical connection from at least one of said first output circuits selectively to several second output circuits, a plurality of result-indicating lights for indicating results consequent upon the selected pitches and hits being made and expected by the opposed players connected to said first and second output circuits.

13. In combination with the game device according to claim 12, a base runner's switch having indicia for registering runners on bases, and a discriminator circuit controlled by said base runner's switch and interconnected between at least some of said output circuits and said result-indicating lights for connecting different result-indicating lights to said output circuits for indicating results in accordance with the men on bases.

14. In combination with the game according to claim 12, an outs switch having indicia for registering outs, and a discriminator circuit controlled by said outs switch and interconnected between at least some of said output circuits and said result-indicating lights for connecting different result-indicating lights to said output circuits for indicating results in accordance with the outs.

15. In combination with the game device according to claim 14, a plurality of lights indicating outs, and a circuit controlled by said outs switch for cumulatively energizing said lights.

16. A game device representing a baseball game comprising a table having indicia thereon representing a baseball playing field, a plurality of lights thereon representing base runners, a base runner switch for selectively connecting said lights to a source of electric power, a first series of lights indicating balls, a second series of lights indicating strikes, a third series of lights indicating outs, switches for selectively connecting the lights of said series to a source of electric power, two pairs of independently operable, multi-posi-

tion selector switches, one selector switch of each pair being disposed to be operated by one of two players and the other switch of each pair being disposed to be operated by the other player, each switch being visible only to the player operating the same, indicia for the first pair of switches indicating kinds of pitches, indicia for the second pair of switches indicating kinds of hits, result-indicating lights on said table for indicating results consequent upon the pitches selected on a switch on the first pair being made when a pitch of the kind selected on the other switch of the first pair is expected and consequent upon a hit of the kind selected on one switch of the second pair being made when a hit of the kind selected on the other switch of the second pair is expected, and a plurality of output circuits from said selector switches controlled jointly by said pairs of switches for connecting said result-indicating lights selectively to a source of power.

17. In combination with the game device according to claim 16, a first discriminator circuit interposed between at least some of said result-indicating lights and some of said output circuits and controlled by said base runner switch for changing the indicated result in accordance with the men on base, and a second discriminator circuit interposed between said first discriminator circuit and at least some of said result-indicating lights and controlled by the switch which controls the third series of lights for changing the indicated results in accordance with the number of outs.
